UNITED STATES PATENT OFFICE.

WILLIAM L. BESSOLO, OF CLEARWATER, CALIFORNIA.

TOOL.

Application filed August 13, 1923. Serial No. 657,024.

This invention relates to tools, and more particularly to tongs or wrenches useful for handling pipes, casing, or like objects.

It is an object of this invention to provide 5 a simple and improved tool of the general character specified.

It is another object of this invention to provide a tool of the character specified having only a few parts, which parts are simple 10 and can be made strong and durable.

The objects and features of my invention will be best and more fully understood by reference to the following description, throughout which description reference is 15 had to the accompanying drawings, in which:

Fig. 1 is a face view of a wrench of the chain type, constructed in accordance with my invention;

Fig. 2 is a detail sectional view of a portion of the wrench, showing the parts provided by my invention; and

Fig. 3 is a detail transverse sectional view, taken as indicated by the line 3—3 on Fig. 2.

In accordance with the broader aspects 25 of my invention the construction provided by this invention is applicable to, or suitable for embodiment in, wrenches and tongs of various sizes, types and constructions. The invention is particularly suited, however, for 30 application to wrenches or tongs of the chain type, so, therefore, I will herein disclose a typical construction embodying my invention in connection with a wrench of the chain type, it being understood, however, that such 35 specific disclosure and reference is not to be considered as limiting my invention to this or any other specific application.

In accordance with my invention the wrench includes, generally, a lever 10, work 40 engaging means 11, and a latch 12 for releasably operatively securing the work engaging means in position for operation.

The lever 10 includes a handle 13, and a head 14 at the outer end of the handle. The 45 head 14 is bifurcated so that it has two spaced side parts 15 which carry and receive the other parts of the tool, as hereinafter described. The head 14 is preferably somewhat enlarged, the side parts 15 being comparatively wide and flat, so that it is strong 50 and rigid. The lever 10 may, in practice, be forged or otherwise formed so that its several parts are integral, making it simple, strong and durable.

55 The work engaging means 11, being of the chain type, is in the form of a chain, having

one end connected directly to the side parts 15, and provided at its other end with a jaw 16. The particular chain illustrated in the drawings includes links 17, connected by 60 suitable pintle pins 18. The side links 17, at the inner end of the chain, extend between the outermost parts of the side parts 15, and are connected with the side parts 15 by a pivot pin 19. The jaw 16 is an arcuate jaw, 65 pivotally connected to the outer end of the chain by a pivot pin 20. The jaw 16 is made sufficiently narrow to pass between the side parts 15, and when the means 11 is in operating position on a pipe P, or the like, the 70 jaw 16 extends between the parts 15. The amount that the jaw extends between the parts is dependent upon the size or diameter of the pipe. If the pipe is small the jaw 75 will extend between the side parts 15 past the inner end of the chain.

In accordance with the preferred form of the invention, a gripping plate 22 is arranged at the outer portions of the side parts 15. The plate 22 extends between the side 80 parts 15 and is supported in recesses 23 provided in the outer parts of the side parts. The outer part or face of the plate is provided with teeth 24 adapted to grip the work to which the tool is applied. The plate is 85 provided with a lug 25, which extends between the side parts 15 and the links 17 at the inner end of the chain, to be held by the pin 19. By this construction the plate is effectively connected with the other parts 90 of the tool, although it is free to be moved or forced out in the recesses toward the work to which the tool is applied. In practice the pin 19 is preferably made to fit more or less tightly through the lug 25 so that the plate 95 does not swing or move freely but normally stays seated in the recesses, as illustrated in the drawings. The preferred form of plate 22 is provided at its back or inner side with a rib 26, which fits between the side 100 parts 15 and acts as a spacer for the side parts. The plate 22 serves to more or less brace and reenforce the side parts 15 at their outer portion and presents a wide gripping face that is particularly effective in 105 gripping the work to which the tool is applied.

The latch 12 is preferably a simple latch, pivotally mounted between the side parts 15 on a pivot pin 27. The pin 27 extends between the inner portions of the side parts 15, 110 and is preferably offset to one side in the

direction from which the jaw extends between the side parts. The latch 12 extends from the pivot pin 27 outwardly and in the direction that the jaw extends between the plates, and is provided at its outer end with teeth 29, adapted to cooperate with teeth 30 provided on the back or outer side of the jaw 16. The teeth 29 and 30 are preferably coarse, and, in practice, are made like gear teeth, as I have illustrated in the drawings. A suitable spring 34 is arranged in connection with the latch to normally urge it outwardly so that the teeth 29 cooperatively engage the teeth 30. It is convenient to make the spring 34 a helical spring, and to locate it between the rear side of the outer part of the latch and a suitable part of the head. In the particular construction illustrated in the drawings, the spring 34 is held in a suitable socket 35 provided in the head in the manner clearly illustrated in Fig. 2. The socket 35 holds the spring in position and permits of its being comparatively long. The latch 25 is provided at one side of the head with a handle 36 and at the other side of the head with a handle 40. The handle 36 cooperates with the head, by engaging it, to limit the outward movement of the latch. In operation the tool is applied to work, for instance, to a pipe P, by arranging the chain around the pipe and extending the jaw 16 between the side parts 15 and between the plate 22 and latch 12. As the jaw 16 is thus moved into position the latch 12 will be depressed against resistance of the spring 34 to allow the teeth 30 to pass the teeth of the latch. When the parts have been thus applied to the pipe by hand as tightly as is convenient, the tool is in position ready for operation. To actuate the tool so that it grips the pipe P the handle 13 is swung in the direction indicated by the arrow A in Fig. 1, so that it pivots about the pin 19 and carries the latch so that it pulls the jaw 16 tightly around the pipe and thus causes the chain to tighten onto the pipe. Further movement of the handle 13 in the direction indicated by the arrow A will cause turning of the pipe P, due to its being gripped by the chain and jaw and will cause the latch 12 to bear against the jaw 16 so that the jaw in turn bears against the plate 22 to hold it tight against the pipe. To release the tool from the pipe the projection or handle 36 is swung out, as indicated by the arrow B in Fig. 1, or the handle 40 is swung in as indicated by the arrow C, causing the teeth 19 of the latch to lift out of engagement with the teeth 30 of the jaw, thus releasing the jaw so that it can be withdrawn from between the side parts 15 and allow releasement of the chain from the pipe.

Having described only a typical preferred form of my invention I do not wish to limit myself to the specific details hereinabove set

forth but wish to reserve to myself any changes or variations that may appear to those skilled in the art or fall within the scope of the following claims:

Having described my invention, I claim:

1. A tool of the character described including, a lever bifurcated at its outer end to have spaced side parts, a gripping plate carried by the outer portions of the side parts, work engaging means having its inner end extending between and connected to the side parts and its outer end adapted to extend between the side parts and engage the back of the plate, and means for releasably operatively connecting said outer end with the lever. 70

2. A tool of the character described including, a lever bifurcated at its outer end to have spaced side parts, the side parts having recesses in their outer end portions, a gripping plate extending between and carried in the recesses, a rib on the back of the plate extending between the side parts to brace them apart, work engaging means having one end connected to the side parts, a pin pivotally connecting the rib between the side parts, and means for releasably operatively connecting the other end of said means with the lever so that it bears against the plate. 85

3. A tool of the character described including, a lever bifurcated at its outer end to have spaced side parts, the side parts having recesses in their outer end portions, a gripping plate pivotally connected with the side parts and extending between the side parts to be carried in the recesses, a rib on the back of the plate extending between the side parts to brace them apart, a chain having one end extending between and connected to the side parts, a jaw connected to the other end of the chain and adapted to extend between the side parts and engage the back of the plate, teeth on the outer part of the jaw, and a toothed latch pivotally carried between the side parts to cooperate with the teeth on the jaw, the axis of pivotal mounting of the latch being located so that the latch extends therefrom to the point where it engages the jaw in the direction in which the jaw extends between the side parts. 100 110

4. A tool of the character described including, a lever bifurcated at its outer end to have spaced side parts, a gripping plate pivotally carried by the outer portions of the side parts, work engaging means having its inner end extending between and connected to the side parts and its outer end adapted to extend between the side parts and bear against the back of the plate, and means for releasably operatively connecting said outer end with the lever. 120 125

In witness that I claim the foregoing I have hereunto subscribed my name this 6th day of August, 1923.

WILLIAM L. BESSOLO.
